US0D1085710S

(12) United States Design Patent (10) Patent No.: US D1,085,710 S
(45) Date of Patent:  Jul. 29, 2025

(54) BAG

(71) Applicant: HERMES SELLIER (Société par actions simplifiée), Paris (FR)

(72) Inventor: Pierre-Alexis Dumas, Paris (FR)

() Term: 15 Years

(21) Appl. No.: 35/522,027

(22) Filed: Feb. 22, 2024

(80) Hague Agreement Data

Int. Filing Date: Feb. 22, 2024

Int. Reg. No.: DM/236126

Int. Reg. Date: Feb. 22, 2024

Int. Reg. Pub. Date: Aug. 23, 2024

(51) LOC (15) Cl. 03-01

(52) U.S. Cl.

USPC D3/246; D3/233

(58) Field of Classification Search

USPC D3/232–233, 243, 245–246

CPC .. A45C 3/06; A45C 1/00; A45C 1/02; A45C 13/18
